TOILET

Edward B. Fry, Detroit, Mich.

Application June 15, 1936, Serial No. 85,199

12 Claims.

(Cl. 4—123)

This invention relates to toilets, and particularly to toilets of the character used in summer cottages, farms, cabins, camp trailers, boats, or in fact any place where the conventional type of plumbing has not been installed. Many types of so-called chemical toilets have been on the market for a number of years using a container into which is placed a quantity of water, and the water is intermixed with some chemical which is supposed to dissolve the refuse, or a deodorant is placed therein which is supposed to overcome the odors emanating from the refuse. Toilets of this type, in addition to being unsanitary, are not odorless, especially during the summer season when a cottage or camp trailer is subject to high temperatures. In addition to the above, some of the chemicals and deodorants sold are very nauseating to many people. It is the primary purpose of the invention herein described to provide a new and improved sanitary toilet which is self-contained, and at the same time providing a toilet approaching the advantages of the modern toilet installed in a location providing running water and modern sewage disposal.

Another object of the present invention is to provide a new and improved toilet comprising a container into which is nested a new and improved bowl and valve assembly so constructed that odors cannot escape from the container below the bowl and valve assembly into the surrounding atmosphere.

More specifically the object is to provide a bowl assembly having a bowl of such shape that it converges toward an opening which has an edge at the lowermost point in said bowl, said opening being inclined upwardly in a direction substantially parallel with one side of said bowl. Such a bowl enables the use of a valve closure which, while effective for emptying the bowl, is not subject to collection of sediment such as would be the case with a valve at the bottom of the bowl. It is also possible with such construction to cover the opening and valve with water thereby effectively sealing the same against escape of odors.

A still further object of the present invention is to provide a new and improved valve and valve operating mechanism for discharging refuse from a bowl assembly into a refuse container below the same.

Another object of the invention is to provide a new and improved flushing means whereby a deposit of fresh water may be allowed to enter the bowl portion of the toilet when desired by the operator.

A further object is to provide new and improved

means for locking the bowl assembly to the container.

A still further object is to provide a new and improved toilet that is at all times odorless and which does not require the use of chemicals or deodorants at any time.

The above and other objects of the invention will appear more fully from the following more detailed description, and from the drawing where-

in:

Fig. 1 is a top plan view of my invention;

Fig. 2 is a section taken substantially on the line

2—2 of Fig. 1; and

Fig. 3 is a portion of a section taken substantially on the line 3—3 of Fig. 1, and showing the top bowl portion clamped to the container portion in accordance with the principles of my invention.

Referring now to the drawing, the numeral 10 designates a container or other sewage receiver of any suitable size or shape, but as shown best in Fig. 2 of the drawing, is cylindrical in shape. The top of the container 10 is bent to form a circumferential flange or ledge 11, the stock being rolled to form a bead 12, for a purpose later to be described. The bowl 13 is formed in one piece, as shown best in Fig. 2, to define a sump or container, the upper portion thereof being bent to form a wide circumferential flange 14, the stock being bent around to form a narrow circumferential flange 15 adapted to be aligned with and rest upon flange 11 of container 10. Interposed between flanges 11 and 15 is disposed a gasket 16 to form a seal between the container 10 and bowl 13 so that neither liquids nor gases may escape from the container 10.

There is provided an annular discharge orifice or opening 17 in the bowl 13, and to open and close this opening when desired there is provided a valve comprising an arc-shaped rubber member 18 secured to a metal disc 19 by means of a bolt and nut 20. The metal disc 19 is hinged upon the pin 21 which passes through a pair of lugs 22 formed on the side of the bowl 13. A spring 23 to hold the valve 18 normally in a closed position, as shown best in Fig. 2, is bent around the pin 21 between the lugs 22, the lower portion of the spring contacting the back of metal disc 19 upon which valve 18 is secured.

It is to be noted that the opening 17 has its lower edge at the lowermost point in the bowl and that the opening is inclined and extends upwardly in a direction substantially parallel with the side of the bowl.

To manually actuate valve 18 there is provided

a lever 24 secured to the handle 25 by means of the pin 26. The lever 24 is journaled in sleeve 27, said sleeve being secured to the outside of the bowl of the toilet in any conventional manner, 5 such as by soldering or riveting, and passes from the exterior to the interior of the toilet, as shown in Figs. 1 and 2. Lever 24 is bowed, within the container, to conform to the shape of bowl 13, and terminates in a cam portion 28. This cam 10 lever 24 is adapted to engage pulley 29 which is secured to pin 30, the pin passing through lug 31 formed on metal disc 19. When lever 25 is moved to the left, as shown in Fig. 2, lever 24, together with cam 28, is moved to the dotted line position of 15 Fig. 2, cam 28 rolling through pulley 29 and, as pulley 29 is secured to the back of metal disc 19, valve 18 is raised from its seat allowing the contents of bowl 13 to be deposited into container 10.

So that the user will know definitely the 20 height of the liquid in container 10, there is provided a projection 32 having an opening 33 from said projection into the container 10. A float 33 is disposed within this tube-like projection and there is secured to the float 33 a measuring 25 rod 34 which passes through an opening in the projection cap so that it may move vertically up or down according to the depth of the liquid in the projection 32. This measuring rod is properly marked to show quarter full, half-full and 30 full so that the user will know exactly when the container 10 should be emptied.

A conventional toilet seat 37 having a cover 38 hinged thereto by means of hinge 39, is secured and rests upon flange 14 by means of bolt and 35 nut 40. The seat 37 protrudes slightly inward, as shown in Fig. 2, to form an overhang beyond the flange 14, so that all refuse will fall directly into the water in bowl 13 and not strike the sides of bowl 13.

To refill the bowl 13 with water after valve 18 40 has been actuated, there is provided a supply tank 41, the same to be secured to the wall above the toilet at any convenient height to provide a gravity feed therefor. This tank is supplied with 45 a tight fitting top to prevent loss of water when the toilet is installed in a camp trailer, or other moving vehicle. A conventional release valve 42 is installed directly below the tank, the same being actuated by means of the lever 43 which has 50 chain 44 secured thereto, said chain being of sufficient length to facilitate the user grasping handle 45 when it is desired to operate valve 42. A flushing pipe 46, having a plurality of staggered apertures 47 therein, is disposed within the 55 upper portion of bowl 13 and is held in place by means of coupling nut 52. Pipe 46 lies directly below and under the overhang of seat 37, the same passing entirely around the inner circumference of bowl 13 and passes out through the 60 side wall of the bowl assembly where it is held in place by means of coupling nut 48. The end of pipe 46 is open, a cork 49 being inserted therein as a plug which may be removed when it is desired to clean the pipe of foreign matter which 65 has collected therein during use. Flexible tubing 50 is used to connect tank 41 with pipe 46, said tubing being secured to the outlet pipe of valve 42 and inlet end of pipe 46 by means of strap 51. Strap 51 enables the user to disconnect flexible tubing 50 from pipe 46 when it is 70 necessary to free the container 10 from the water supply tank 41.

Clamping means 53 are provided to secure the bowl 13 to the container 10, said means comprising, as shown best in Fig. 3, a clip 54 secured

to the bowl by means of a rivet 55. The clip 54 is hinged on pin 56 and hooked member 57 is hinged within the member 54. As shown best in Fig. 3, the hooked member 57 is shown engaged upon the bead 12 to secure the bowl and container sections of the device in locked engagement. To release securing means 53 the clip 54 is moved to the right to the dotted line position of Fig. 3, this allowing the hooked member 57, which is pivoted on pin 58, to free itself from bead 12.

A bail 59 is secured to the container 10 by any suitable means such as the ears 60 which are aligned on opposite sides of the container, as shown best in Fig. 1. The bail 59 enables the 15 user to conveniently carry the device when it is necessary to empty the container.

There is provided an opening in the lower portion of the container 10 to which is secured a threaded projection 61. A threaded cap 62 is 20 adapted to engage the threaded projection 61 and close the opening into the container.

The manner in which the device operates is as follows:

The water supply tank 41 is first filled to 25 capacity and the cover placed thereupon. To transfer a quantity of water from the supply tank 41 to the bowl 13, the user actuates valve 42 by pulling upon handle 45 which in turn operates lever 43. The water flows by gravity down conduit 50 into flushing pipe 46 where it is released through the plurality of staggered apertures 47 into bowl 13. When the desired quantity of water has been released, the handle 45 is released and valve 42 then closes automatically. As valve 35 18 is in a closed position, as shown in Fig. 2, the water remains in the bowl 13 and the toilet is ready for use. When it is desired to dump the contents of bowl 13, the user operates lever 24, by means of handle 25, moving the same from 40 right to left as illustrated in Fig. 2. Lever 24 being journaled in sleeve 27 and terminating in a cam 28, which in turn passes through pulley 29 which is secured to the back of valve 18, valve 18 is swung to an open position against spring 23 to 45 the dotted line position shown in Fig. 2. The water in bowl 13 then passes out through opening 17 and dumps into container 10. When handle 25 is released by the user, valve 18 is returned to its normal position, as shown in Fig. 2, by means of spring 23. Inasmuch as valve 18 is of rubber and the circumference of opening 17 is rounded, the arc-shaped rubber face of the valve forms a liquid tight seal. When valve 18 has again been closed, the operator then releases valve 42 by means of chain pull 45 and another quantity of water is deposited in bowl 13. It will be noted from Fig. 2 that bowl 13 is so shaped that all refuse will drop directly into the water in the bowl and will not strike the unprotected sides of the bowl. Inasmuch as the water enters the bowl 13 through apertured pipe 46, and as the holes in pipe 46 are staggered the water is directed toward the interior of the bowl in a plurality of directions thus effectively clearing the bowl with a minimum amount of water, a result of utmost importance in a unit to be used where only a limited quantity of water is available. When it is desired to clean flushing pipe 46 of any sediment that might lodge therein, and therefore plug apertures 47, the user simply removes the cork plug 49, Fig. 1, which closes the open end of flushing pipe 46, and any foreign matter lodged in the pipe will be carried away through this opening.

When the gauge stick 34 discloses that the container 10 should be emptied, the user disengages conduit 50 from flushing pipe 46, by loosening strap 51. Bail 59 may then be swung to a position above the device so that the container may be transported. If two people wish to carry the container, the same could be provided with a handle on each side thereof similar to the handles commonly seen on large ash containers. During the period when the device is being transported to the locality where the refuse is to be buried, the valve 18 remains closed and no odors may escape from the container 10. To empty the container, the clamping means 53 are opened by moving the clip 54 to the right, as shown in Fig. 3, so that the hooked member 57 is freed from the bead 12 of the container 10. The entire bowl assembly is then removed from the lower container 10 and the contents dumped. If the user does not wish to carry the entire device to the dumping locality, the bowl assembly may be removed and a top cover which fits neatly over the bead 12 of container 10, may be installed to prevent spilling and splashing of the contents of the container during the carrying period. Container 10 may also be emptied by removing cap 62 from projection 61 and tilting the container sufficiently to allow the contents to flow out the opening in the container.

Should it be desired to install my device in a location where there is already in use a toilet using a tank or other means of sewage disposal, the container 10 may be constructed as an open-ended cylinder which may be fastened to the floor directly over the opening leading to the tank below. This would do away with the necessity of dumping the container and also do away with the disagreeable odors so prevalent with toilets of the tank type, the valve 18 being a complete seal against any escape of gases from below ground.

I have described a new and improved toilet that will be cheap to manufacture and assemble, and yet it will provide the user with the same high efficiency of operation that one expects from the new and improved toilets installed in the newer buildings throughout the country. It provides an ideal odorless toilet for camp trailers where the problem of refuse disposal has been one of real concern, inasmuch as a trailer is on the road during the heat of summer and if a chemical is used, there is always some odor, even if it is that of the so-called deodorant itself. The water supply tank is fully enclosed so that there is no chance of spilling the contents while en route.

While I have shown and described a satisfactory constructional example embodying the principles of the present invention, it will be understood that many changes, variations and modifications may be resorted to without departing from such principles.

I claim:

1. A toilet comprising a container, having a gauge and a drain therein, a bowl assembly superimposed upon said container, said bowl assembly being arc-shaped in cross-section, a flushing conduit discharging into the bowl, water supply means for flushing and filling said bowl including a supply tank, means for conveying water from said tank to said flushing conduit, and means for coupling said conveying means to said flushing conduit.

2. A toilet comprising a main container having a gauge and a drain, a bowl assembly, a flushing conduit discharging into the bowl, water supply

means for flushing and filling said bowl, means for dumping said water into the main container, said gauge comprising an auxiliary container adjacent said main container, an opening between said main container and said auxiliary container, a float having measuring means secured thereto located in said auxiliary container, said float being responsive to the height of liquid in said main container.

3. A toilet comprising a sewage receiver, a bowl supported above said sewage receiver, said bowl having an opening with its lowermost edge at the lowest point in said bowl and inclined upwardly in a direction substantially parallel with one of the sides of said bowl, and a valve member movable to contact and seal said opening.

4. A toilet comprising a sewage receiver, a bowl supported above said sewage receiver, said bowl having an upwardly inclined opening with an edge of said opening at the lowermost point in said bowl, and a valve member movable to contact and seal said opening.

5. A toilet comprising a bowl having an upwardly inclined opening with an edge of said opening at the lowermost point in said bowl, and a valve member to contact and seal said opening mounted to swing on a pivot adjacent the upper edge of said opening.

6. A toilet comprising a sewage receiver, a bowl supported above said sewage receiver, said bowl shaped to converge to an upwardly inclined opening with an edge of said opening at the lowermost point in said bowl, a valve movable to contact and seal said opening, and means to supply a quantity of water to said bowl sufficient to cover said opening and valve.

7. A toilet comprising, a bowl shaped to converge to an upwardly inclined opening with an edge of said opening at the lowermost point in said bowl, a valve movable to contact and seal said opening, and a flushing conduit near the top of said bowl with staggered openings therein to direct water in a plurality of directions toward the center of said bowl.

8. A toilet comprising a sewage receiver, a bowl having an opening and supported above said sewage receiver, a valve movable to contact and seal said opening, and a flushing conduit comprising an annular projection near the top of said bowl with staggered openings therein to direct water in a plurality of directions toward the interior of said bowl.

9. A toilet comprising a sewage receiver, a bowl having an opening and supported above said sewage receiver, a valve movable to contact and seal said opening, a flushing conduit near the top of said bowl with staggered openings therein to direct water in a plurality of directions toward the interior of said bowl, and a removable closure means provided at one end of said flushing conduit whereby said conduit may be cleaned.

10. A toilet comprising a sewage receiver, a bowl supported above said sewage receiver, said bowl shaped to converge to an upwardly inclined opening so positioned that its lower edge is at the lowermost point in said bowl, a valve movable to contact and seal said opening, means manually holding said valve in closed position, manually operable means for actuating said valve, and means to supply a quantity of water to said bowl sufficient to cover said opening and valve.

11. A toilet comprising a sewage receiver, a bowl assembly with a bowl shaped to converge to an

upwardly inclined opening with an edge of said opening at the lowermost point in said bowl, a valve movable to contact and seal said opening, means to supply a quantity of water to said bowl sufficient to cover said opening and valve, and a clamping member serving to seal said bowl assembly to said sewage receiver.

12. A toilet comprising a sewage receiver, a bowl assembly having a bowl shaped to converge 10 to an upwardly inclined opening with an edge of said opening at the lowermost point in said

bowl, a valve movable to contact and seal said opening, water supply means for flushing and filling said bowl including a supply tank, a flushing conduit located near the top of said bowl, means for delivering water from the supply tank to the flushing conduit, and a manually controlled water supply valve for releasing a measured quantity of water from the supply tank to said bowl to be retained in said bowl by said valve.

EDWARD B. FRY.
